UNITED STATES PATENT OFFICE.

CROSBY FIELD, OF BROOKLYN, NEW YORK, ASSIGNOR TO BRILLO MANUFACTURING COMPANY, INC., A CORPORATION OF NEW YORK.

CLEANING PAD.

Application filed June 24, 1924. Serial No. 721,970.

Cleaning pads of fibrous material as, for instance, wool, particularly steel wool, are commonly used in combination with soap. In fact, packages of steel wool scouring pads as commonly marketed for many years past have included a cake of soap for use in combination with the pad. I have observed that when these cakes of soap are used between two of the pads, the steel wool tends to embed itself in the soap, but I find that an ordinary cake of soap is likely to be too thick for convenient use in such relation; moreover, its size and weight are such that the embedding is seldom sufficient to make a bond secure enough for practical purposes, when the article is in prolonged use and my present invention contemplates a practically permanent association of the soap with the steel wool in an article comprising a number of thin sheets of soap interleaved between a plurality of steel wool layers or pads, the steel wool embedding itself in the soap and the composite article being supplied about part of its surface, with a binder. Such binder may be somewhat like the binding of a book covering an edge and part of two faces of the composite article, or it may be in the nature of a band for binding layers together. In any case, the article is preferably used with the exposed edges of the leaves of soap and of steel wool applied to the article to be cleansed.

Certain embodiments of my invention will be readily understood from the following description in connection with the accompanying drawings, in which

Fig. 1 is a perspective view showing one embodiment of my invention;

Fig. 2 is an end elevation showing a modification;

Fig. 3 is a perspective view showing another modification;

Fig. 4 is an end elevation showing another modification; and

Fig. 5 is a similar view of a further modification.

In Fig. 1 thin sheets of soap 1, 1, etc., are shown as interleaved between the more or less matted layers or pads 2, 2, etc., the outermost layer at the end of the series being of steel wool.

The layers are preferably protected and held in assembled position as, for instance, by flexible material, fabric, or metal 3, which as shown in Fig. 1 is arranged some-

what like the binding of a book, except that the parts corresponding to the covers are shorter than the leaves that are bound thereby. The exposed sides of the metal wool may be used for scouring purposes without causing the soap to contact with the article being cleaned, but the more ordinary use would be application of the edges of the layers to the article, that is, the surface edges lowermost in Figs. 1 and 2.

In Fig. 1 I have indicated that the binding is secured by waterproof cement such as rubber cement and the ends of the leaves embraced by the binding, but not engaged thereby, may be secured by a coating of rubber cement 4. Such waterproof cement may be used as the sole binding for the article, the binding sheet 3 being omitted.

In Fig. 4 I have shown a modification wherein the arrangement of the soap and steel wool layers may be substantially the same as Fig. 1, but the binding 4^a consists of a material which is carried around the side edges of the pad as well as across the back and down the side. Such bindings 80 may be tin foil or sheet lead.

Fig. 3 shows a modification in which a single soap sheet 1^a and a single sheet of steel wool 2^a is rolled up in a spiral, unrolling being prevented by a binder 3^a which 85 may be either a cup or a band and may consist of fabric or of tinfoil or may be merely a coating of the waterproof cement.

Fig. 4 shows another modification in which a core of metal wool 11 has wound 90 around it a cylindrical sheet of soap 12 about which is a cylindrical layer of metal wool 11^a about which is a second cylindrical sheet of soap 12^a. Outside of the latter and forming the outermost layer, is a final sheet 95 of metal wool 12^b.

As indicated in Fig. 5, the spiral arrangement of Fig. 3 may be flattened down to an oval or rectangular pad if desired. The same flattening may be practised with the 100 concentric arrangement of Fig. 4.

As regards Figs. 2 and 4, it will be noted that the center or core of the cylinder is of metal wool, which I find to be a distinct advantage over having a core of soap. One 105 reason is that where the soap is concentrated in a central core, the metal wool is apt to strip backward and expose the core. If the latter is stiff enough to endure in such a situation, it requires more soap than is 110

likely to be needed in connection with and during the life of that particular pad. With my arrangement, the soap is in definite quantity, definitely arranged and in general is likely to wear back or bend or pack or become upset into and between the steel wool layers, under the conditions of use. It will be understood that in practice the pad will wear down and flatten out and that eventually portions of the binding or cover may be torn off or stripped back until the entire pad has been used up.

The form shown in Fig. 1, when used in the manner described, is likely to open up and flatten down and can be used up as completely as the ordinary pad.

In many cases it will be found that colloidion is a very satisfactory cement to be

used either itself as a covering or as a means for securing the fabric or metal coverings. 20

I claim:

1. A scouring pad comprising a composite laminated body formed of relatively thick layers of matted metal wool alternating with relatively thin layers of soap. 25

2. A scouring pad comprising a composite laminated body formed of relatively thick layers of matted metal wool alternating with relatively thin layers of soap, and a binding for securing the layers, said binding extending across the back edges of said layers and part way over the exterior layers. 30

Signed at New York, in the county of New York, and State of New York, this 23rd day of June, A. D. 1924.

CROSBY FIELD.
